(57) **CLAIM**

The ornamental design for a chair, as shown and described.

DESCRIPTION

A portion of the disclosure of this patent document contains material for which a claim for copyright is made. The copyright owner has no objection to the facsimile reproduction by anyone of the patent document or the patent disclosure, as it appears in the US Patent and Trademark Office patent file or records, but reserves all other copyrights whatsoever.

FIG. 1 is a front perspective view of an ornamental design for a chair;

FIG. 2 is a front view thereof;

FIG. 3 is a rear view thereof;

FIG. 4 is a left elevation view thereof;

FIG. 5 is a right elevation view thereof;

FIG. 6 is a top view thereof;

FIG. 7 is a bottom view thereof; and,

FIG. 8 is a magnified view of a top portion of a chair back thereof.

The dashed broken line in FIG. 8 shows a break line and forms no part of the claimed design.

1 Claim, 8 Drawing Sheets
